RADIO RECEIVING SYSTEM

Filed Feb. 23, 1928

UNITED STATES PATENT OFFICE

FREDERICK A. KOLSTER, OF PALO ALTO, CALIFORNIA, ASSIGNOR TO FEDERAL TELEGRAPH COMPANY, OF SAN FRANCISCO, CALIFORNIA, A CORPORATION OF CALIFORNIA

RADIO RECEIVING SYSTEM

Application filed February 23, 1928. Serial No. 256,101.

This invention relates generally to systems for the reception of signal energy of radio frequency.

Radio receiving systems generally utilize a plurality of vacuum tubes or electron relays connected together in cascade for repeating the received or locally modified signal energy. A number of the electron relays usually function as a multistage radio frequency amplifier, one relay operates as a detector or integrating device, and the remainder operate as audio frequency amplifiers for supplying a suitable loud speaker or other translating device. Where the receiver is made selective over a substantial range of frequencies,—as for example a broadcast receiver intended to receive signals within the broadcast range of from 200 to 550 meters,—the coupling devices interposed between certain of the electron relays are made selectively tunable and are frequently adjustable manually by means of a unitary control. One form of coupling device commonly used consists of an untuned primary coil coupled to a secondary coil which is tuned by means of a variable condenser. A receiver of this kind will not have uniform sensitivity over the entire wavelength range for which it is adapted to receive. When receiving on the lower wavelengths there is a regenerative action which makes the receiver more sensitive than for the longer wave-lengths, while for the wave-lengths along the middle of the range, the receiver has good sensitivity. Strong regenerative action on the shorter wave-lengths is objectionable in that it tends to cause the system to break into oscillation, and thus renders it unstable in operation. The tendency to oscillate may be minimized by inserting grid resistances or by other suitable means, in which event if the receiver is rendered sufficiently stable the sensitivity at the shorter wave-lengths is less than at the wave-lengths along the middle portion of the wave-length range. Thus a stabilized receiver of this kind will have poor sensitivity for both short and long wave-lengths but better sensitivity for the intermediate wave-lengths.

It is an object of this invention to devise

simple means for compensating for the non-uniform sensitivity of a radio receiver.

It is a further object of this invention to devise means which may be interposed between the source of signal energy and the first electron relay stage of a radio receiver, which will function to compensate for the non-uniform sensitivity of the receiver.

It is a further object of this invention to devise means which may be interposed between a source of signal energy and the first electron relay stage of the radio receiver for compensating for the non-uniform characteristic of the receiver and also for rendering the receiver immune to changes in the electrical characteristics of the source of energy.

Referring to the drawings:

Figure 1 is a circuit diagram of a radio system incorporating the system of this invention.

Fig. 2 is a detail circuit diagram of one of the radio frequency amplifiers employed in the system of Fig. 1.

Fig. 3 is a detail diagram illustrating the operation of the electrical device coupling the antenna circuit to the first electron relay of the system of Fig. 1.

Fig. 4 is a detail diagram illustrating an alternative arrangement to that shown in Fig. 3.

Fig. 5 comprises curves drawn to illustrate the nature of the reactances of the coupling device shown in Figs. 1 and 3.

Fig. 6 comprises curves illustrating the non-uniform characteristic of a receiver and the manner in which it is compensated.

The system of my invention may be outlined briefly as comprising a radio receiver which utilizes a cascade radio frequency amplifier selectively tunable over a substantial wave-length range. Interposed between the first stage of the amplifier and the radio antenna or other source of signal energy, is an electron relay of the three element type, and the grid or input circuit of this relay is connected to the antenna thru a special compensating coupling device. This coupling device is constructed so that without physical adjustment it will tend to automatically compensate for the non-uniform response char-

acteristic of the receiver. The use of a relay in this manner also renders operation of the receiver immune from changes in the electrical characteristics of the antenna or other 5 source of energy with which the receiver is used.

Referring to Fig. 1 of the drawings, a plurality of electron relay amplifier stages 11, 12 and 13, are shown connected together in 10 cascade to form a radio frequency amplifier. Current from the last amplifier stage is applied to a suitable detector or integrating device 14, the output of which may be repeated thru a single or multistage audio 15 frequency amplifier 15 and impressed upon a suitable loud speaker or translator 16. In accordance with the usual practice in such receivers, I have shown tuned coupling devices 18 for coupling the first amplifier stage 20 11 to a source of signal energy, for coupling the amplifier stages together, and for coupling the last stage 13 to the detector 14. These coupling devices are preferably of simple construction, comprising for example 25 primary and secondary inductances 19 and 21, the secondary inductance being tuned by means of a variable condenser 22. Each variable condenser forms what may be termed a variable tuning element and these elements 30 are preferably mechanically interconnected to a unitary control so that they may be simultaneously tuned by an operator. With a receiver of this kind all of the amplifier stages are kept in resonance by the unitary 35 control, and by adjustment of this control the receiver may be selectively tuned to receive any one frequency within a given wavelength range.

One stage of the radio frequency amplifier 40 is shown in Fig. 2. I have shown the electron relay 23 of that stage connected to the secondary of a preceding coupling device 18, and its plate circuit connected to the primary coil of a succeeding coupling device. Because of the inherent grid plate capacitance 45 of the electron relay, and because of inter-magnetic coupling between the input and output circuits, an amplifier constructed in this manner tends to oscillate locally and to become unstable when tuned to relatively low 50 wave-lengths, since feed back action is more pronounced upon the shorter than upon the longer wave-lengths. Although it is unstable 55 at the low wave-lengths the amplifier is more efficient due to regenerative action, and thus the receiver is more sensitive when tuned to the shorter wave-lengths than when tuned to the longer wave-lengths. In other words the receiver has a non-uniform response 60 characteristic.

Since instability in a receiver is an undesirable feature, I preferably provide means for minimizing the same, as for example a resistance 65 24 inserted in series with the grid of each of the radio frequency amplifier tubes

23. This introduces a resistance component in the relay circuits which tends to decrease the tendency of the cascade radio frequency amplifier as a whole to oscillate and reduces regeneration. The corresponding reduction 70 in regenerative action however reduces the sensitivity of the receiver at the shorter wave-lengths. Such a receiver will have a response curve somewhat as shown by the curve 75 1 of Fig. 6, which has been plotted for the broadcast wave-length range of from 200 to about 550 meters. As indicated by this curve the response of the receiver has a drooping characteristic at both limits of the wave-length range. The loss in sensitivity at the 80 longer wave-lengths is due in part to the characteristics of the coupling devices 18.

In accordance with this invention I provide means for increasing the sensitivity of the receiver at both limits of the wave length-range, without however rendering the receiver unstable because of regeneration. As shown in Fig. 1 the particular means which I employ includes an additional electron relay 26 having its output circuit connected 90 to the coupling device 18 in the input circuit of the amplifier 11, and having its input or grid circuit associated with a suitable source of signal energy by means of a special coupling device 27. The source of energy has 95 been indicated as comprising a radio antenna 28 and ground connection 29. The coupling device 27 is so designed as to give different impedance effects at different frequencies, whereby in effect more efficient transfer of 100 energy is secured from the antenna relay 26 for frequencies near the limits of the wave-length range, than for frequencies lying between the limits.

In one specific embodiment of my invention, device 27 comprises two branch paths for currents flowing in the antenna circuit, one path being formed by the inductance L_1 , and the other path being formed by the inductance L_2 and a capacitance C_2 in series 110 with inductance L_2 . For the capacitance C_2 I prefer to utilize the inherent grid-cathode capacitance of the relay 26. Inductances L_1 and L_2 are so selected and proportioned, that the combination of elements reaches or approaches a condition of resonance near each 115 limit of the wave-length range for which the receiver is adapted to operate.

To explain the design and mode of operation of the coupling device 27, reference is 120 made to Fig. 3 in which a capacitance C_3 has been substituted for the capacitance of the antenna 28, the inductance and resistance of the antenna circuit being ignored for purposes of explanation. This arrangement has 125 two different periods of freedom or points of resonance. At one resonant frequency current may be considered as flowing thru capacitance C_3 and thru inductance L_1 and reactance $L_2 C_2$ taken in parallel. At another 130

resonant frequency circulatory current flows between inductance L_1 and the reactance formed by L_2C_2 . This effect may be more clearly explained by referring to the curves of Fig. 5. Curve 2 indicates the reactance of the arrangement considering L_1 and L_2C_2 as a unit shunted by capacitance C_3 . As shown this arrangement has a resonant point at the wave-length indicated by the dotted line 32 which is selected near the lower frequency limit of the wave-length range. Preferably this resonant point lies outside of the wave-length range and for this reason line 32 in the illustration occupies approximately the 600 meter point corresponding to the broadcast range of 200 to 550 meters. Curve number 3 indicates the reactance of the arrangement shown in Fig. 4 comprising L_2 and C_2 in series shunted by capacitance C_3 . The reactance of this arrangement is preferably made negative throughout the wave-length range and increases negatively from the shorter to the longer wave-length limits. At some point near the lower wave length limit, say for example at a wave-length of about 175 meters indicated by dotted line 33, there is also a condition of resonance since the positive reactance indicated by curve 2 is equal to the negative reactance of curve 3. In other words distance a is equal to distance b . Thus a condition of resonance will be attained or approached near each limit of the wave-length range for the arrangement shown in Fig. 3.

When the input circuit of relay 26 is connected across to the capacitance C_2 , as in the arrangement shown in Fig. 1, it is obvious that the transfer of high frequency energy from the antenna to the relay will be most effective near the two resonant points of the circuit arrangement shown in Fig. 3. In other words near the limits of the wave-length range, a tighter effective coupling will be secured between the antenna and the relay 26 than at wave-lengths lying along the middle of the wave-length range. Thus the device 27 taken with the relay 26 will have non-uniform sensitivity for different selected frequencies, but this non-uniformity is of such a character as to compensate for the non-uniformity of the receiver.

Referring again to Fig. 6, the curve 4 indicates the resultant or compensated sensitivity of the entire system. As shown by this curve the sensitivity of the receiver near the limits of the frequency range has been substantially increased to practically the same value as the sensitivity for intermediate wave-lengths. The resulting system now has more nearly uniform sensitivity over the entire wave-length range. It is to be noted however that this uniform sensitivity is not obtained by sacrificing stability, since the operation of the radio frequency amplifier of the receiver still has a sensitivity characteristic

corresponding to curve 1. I have found that it is preferable to keep the resonant point indicated by the dotted line 33 (Fig. 5) outside the wave-length range, altho the resonant point at the other limit of the wave-length range indicated by line 32 may fall within rather than without the wave-length range. The exact location of these resonant points with respect to the wave-length range depends somewhat upon the characteristics of the receiver supplied by the relay 26.

The system as explained above possesses another important advantage in that the operation of the receiver is practically unaffected by changes in the electrical characteristics of the antenna 28. The system may be connected to antennæ of different lengths and different electrical characteristics, without making an individual compensating adjustment for the tuning of the first coupling device 18. Thus a definite movement may be imparted to the condenser 22 of the first coupling device 18 by the unitary control, and this movement may remain exactly the same with respect to the other condensers 22 irrespective of the nature of the antenna being used. This feature is especially desirable with broadcast receiving sets since with my invention they may be finally adjusted at the factory and will operate with good efficiency when connected to a variety of antennæ. The capacitance C_2 is made as small as possible, so that capacitance C_3 representing the antenna ground capacitance, is relatively large in proportion. Thus while variations in the characteristics of the antenna will have some effect upon shifting the resonant points of the coupling device 27, this effect will not be sufficiently great to have a material effect upon the overall uniformity of the system. A small capacitance may be shunted across the grid and filament of relays 26 to supplement the grid cathode capacitance of this relay, but in any event the capacitance C_2 should be kept relatively small.

I prefer in practice to introduce a substantial resistance in series with inductance L_2 and capacitance C_2 . For example this resistance may be formed by winding a coil of resistance wire to form the inductance L_2 . Resistance introduced in the series with L_2 has the effect of broadening the high frequency resonant peak of the coupling device 27, but has little effect upon the longer wave-length resonant peak. By the use of resistance in this manner, I am enabled to make the curve 4 more nearly linear near the lower wave-length limit and thus to prevent any possible instability of the relay 26 when the receiver is operated at low wave-lengths.

I claim:

1. In a system for the reception of signals of carrier frequency, a source of signal energy, amplifying and translating means hav-

ing non-uniform sensitivity for different carrier frequencies impressed upon the same, and means interposed between the source and said amplifying and translating means for 5 repeating signal energy from said source into said amplifying and translating means, said last named means having non-uniform sensitivity for different carrier frequencies of a character tending to compensate for the non-uniform sensitivity of the amplifying and translating means.

2. In a system for the reception of signals of carrier frequency, a source of signal energy, a radio frequency amplifier, detecting 15 and translating means receiving energy from the amplifier, said cascade amplifier having non-uniform sensitivity for signal energy of different frequencies, and means interposed between the source and said amplifier 20 for repeating signal energy from said source to said amplifier, said last named means having non-uniform sensitivity for signal energy of different frequencies but of a character tending to compensate for the non-uniform 25 sensitivity of the amplifier.

3. In a system for the reception of signals of carrier frequency, a source of signal energy, a radio frequency amplifier, detecting and translating means receiving energy 30 from the amplifier, said cascade amplifier having non-uniform sensitivity for signal energy of different frequencies, and means including an electron relay interposed between the source and said amplifier for repeating signal energy from said source to said amplifier, said last named means having non-uniform sensitivity for signal energy of different frequencies but of a character tending to compensate for the non-uniform 35 sensitivity of the amplifier.

4. In a system for the reception of signals of carrier frequency, a source of signal energy, a radio frequency amplifier, detecting and translating means receiving energy from 45 the amplifier, said cascade amplifier having non-uniform sensitivity for signal energy of different frequencies, an electron relay having its output coupled to the input of said amplifier, and reactive means coupling said source with the input of said relay for causing 50 said relay to have non-uniform sensitivity for signal energy of different frequencies received from said source, the non-uniform sensitivity of said relay being of such a character as to substantially compensate for the non-uniform sensitivity of the 55 amplifier.

5. In a system for the reception of signals of carrier frequency, a source of signal energy, a receiver including a plurality of electron relays coupled in cascade and having a plurality of individual tuning elements 60 simultaneously variable by a unitary control whereby the receiver may be selectively tuned

over a wide range of radio frequencies by movement of said unitary control, said receiver having a non-uniform response characteristic for energy of different frequencies, and means interposed between said receiver 70 and said source for preventing changes in the constants of said individual tuning elements due to variations in the electrical properties of said source, said means serving to repeat signal energy from said source to 75 the receiver in such a manner as to compensate for the non-uniform response characteristic of the receiver.

6. In a system for the reception of signals of carrier frequency, a source of signal energy, a receiver including a plurality of electron relays coupled in cascade and having a plurality of individual tuning elements simultaneously variable by a unitary control whereby the receiver may be selectively tuned 80 over a wide range of radio frequencies by movement of said unitary control, said receiver having a non-uniform response characteristic 85 for energies of different frequencies, and means interposed between said receiver and said source for rendering said individual tuning elements independent of variations in the electrical properties of said source, said means comprising an electron 90 relay having its output circuit coupled to the input circuit of the receiver, and a plurality of reactive elements associated with the input circuit of said relay and the source of signal energy, said elements being so arranged as to automatically vary the effective 95 electrical coupling between said source and said relay in accordance with a variation in the frequency of signal energy, said variable electrical coupling serving to compensate for the non-uniform response characteristic 100 of the receiver.

7. In a system for the reception of signal energy of carrier frequency, a source of signal energy, an electron relay having an anode, a cathode, and a grid controlling the space 110 charge between the anode and cathode, said relay having an effective grid-cathode capacitance, a cascade electron relay system coupled to the output of said amplifier, a plurality of reactances arranged to form parallel paths for current received from said source, each of said paths including at least one inductive element, and one of said paths including a series capacitative element 115 formed at least in part by the grid-cathode capacitance of the relay, said elements being so proportioned and related as to provide a device which affords a variation in the effective electrical coupling between the source and said relay in accordance with a variation 120 of the frequency of incoming signals and without physical adjustments.

8. In a system for the reception of signals of carrier frequency, a receiver selectively tunable over a substantial wave-length 125

range and having a greater response at wavelengths near the middle of said range than near the ends, a source of signal energy, and coupling means interposed between said source and said receiver, said coupling means having two points of resonance at frequencies lying adjacent the limits of said wave length range.

9. The combination of a high frequency amplifier tunable over a range of frequencies and having greater sensitivity at frequencies near the middle of said range than near the ends thereof, with an input circuit coupled thereto by a uni-directional translating device, said input circuit comprising a reactance element in shunt to said uni-directional translating device and other reactance elements constituting with said first reactance element a resonant circuit at frequencies adjacent the limits of said range.

10. The combination of a high frequency amplifier tunable over a range of frequencies and having non-uniform sensitivity over said range with an input circuit therefor comprising a capacity element effectively in shunt with said amplifier, a first inductance and a second inductance in series with said capacity element and a second capacity element larger than said first capacity element in shunt to one of said inductances.

11. A radio frequency amplifier tunable over a range of frequencies and having non-uniform sensitivity over said range, a signal energy input device and means interposed between said amplifier and said input device to modify the efficiency of the latter compensatively with respect to the sensitivity of said amplifier for different frequencies.

12. A signal energy absorption device in association with reactances causing the same to have two resonance points, an amplifier network the sensitivity of which tends to vary throughout the operating range of frequencies of signal energy inversely to the resonant characteristics of said absorption device in association with said reactances, and a thermionic relay interposed between said reactances and said amplifier network.

In testimony whereof, I have hereunto set my hand.

DISCLAIMER

1,830,948.—*Frederick A. Kolster, Palo Alto, Calif. RADIO RECEIVING SYSTEM.*
Patent dated November 10, 1931. Disclaimer filed October 23, 1934, by
the assignee, *Federal Telegraph Company*.

Hereby enters the following disclaimer:

In claim 1, no claim is made to the combination recited except where the means interposed between the source and the amplifying and translating means is resonant at a frequency near the lower end and at a frequency near the upper end of a frequency range containing the different carrier frequencies.

In claim 2, no claim is made to the combination recited except where the means interposed between the source and the amplifier is resonant at a frequency below the lower end and at a frequency near the upper end of a frequency range containing the different carrier frequencies.

In claim 3, no claim is made to the combination recited except where the electron relay has no tunable element in its input circuit.

In claim 4, no claim is made to the combination recited except where the input of the electron relay contains no tunable element.

In claim 5, no claim is made to the combination recited except where the means is resonant at a frequency below the lower end and at a frequency above the upper end of the range.

In claim 6, no claim is made to the combination recited except where the input circuit of the electron relay contains no tunable element varied by the unitary control.

In claim 11, no claim is made to the combination recited except where the means is resonant at a frequency near the lower end and at a frequency near the upper end of the range.
